UNITED STATES PATENT OFFICE.

WILHELM B. BRONANDER, OF MONTCLAIR, NEW JERSEY, ASSIGNEE TO INTERNATIONAL FIRE EQUIPMENT CORPORATION, OF WEST NEW BRIGHTON, NEW YORK, A CORPORATION OF DELAWARE.

FIRE-EXTINGUISHER SUPPORT.

Application filed February 23, 1927, Serial No. 170,173. Renewed February 24, 1928.

This invention relates to fire extinguishers. More particularly stated, the invention relates to the grenade type of fire extinguisher and to a holder or support for the grenade.

5 This invention has for its salient object to provide a support for a grenade, so constructed and arranged that in case of fire the grenade will automatically drop, break, and dispense the fire extinguishing fluid.

10 Another object of the invention is to provide a bracket or holder for grenades comprising few parts and a structure that can be economically manufactured.

15 Further objects of the invention will appear from the following specification taken in connection with the drawings, which form a part of this application, and in which

Fig. 1 is a front elevation of a device constructed in accordance with the invention;

20 Fig. 2 is a sectional elevation taken substantially on line 2—2 of Fig. 1;

Fig. 3 is a top plan view of the structure shown in Fig. 1;

25 Fig. 4 is an elevational view on an enlarged scale of a portion of the plate for retaining the resilient supports under tension; and

Fig. 5 is a sectional elevation taken substantially on line 5—5 of Fig. 4.

30 The invention briefly described consists of a grenade support comprising a bracket or plate adapted to be secured to a wall or other supporting structure, a pair of resilient supporting members adapted to embrace the grenade and form the support therefor and means including a fusible element engaging the supporting members and retaining them under tension. In the form of the invention shown, the means for holding or retaining the

35 supporting members under tension is located on the opposite side of the grenade from the bracket or plate on which the members are mounted and when the fusible element melts, the resilient supports spring apart, permitting the grenade to drop. The grenade is

40 preferably formed of glass or other frangible material and is broken when it strikes the floor, thereby freeing the fire extinguishing liquid, such as carbon tetrachloride, contained

therein. Further details of the invention will 50 appear from the following description.

In the particular form of the invention shown, there is illustrated a plate or bracket 10 having an opening 11 therein adapted to receive a screw or other retaining member. 55 The plate is preferably formed of sheet metal and has punched therefrom or secured thereto two sets of pivot lugs or loops 13 and 14.

The grenade is supported in a pair of longitudinally curved supporting members 16 and 17 formed of resilient material, such as resilient wire stock. These members have substantially straight end portions 20 and 21 which are disposed in parallel relation to each other when the supporting members are 65 placed under tension as shown in Fig. 3.

The members 16 and 17 are bent laterally as shown at 22 and 23 and at the ends of the lateral portions, are bent downwardly or at substantially right angles to the plane of the 70 body portion of the supporting members.

The downwardly extending portions 25 are pivoted in the lugs or loops 13 and 14. The bends 22 and 23 are so formed that in order to bring the body portions of the members 16 75 and 17 to the position shown in Fig. 3, or to the position in which they are adapted to support a grenade 30, the members must be placed under tension. In order to retain the supporting members under tension, a plate 31 80 is mounted on the outer ends 20 and 21 of the supporting members 16 and 17. The plate has an opening 33 adjacent one edge thereof for receiving the end 21 of the member 17. At its opposite edge, the plate 31 85 has formed thereon, an inwardly extending elongated notch 35. A strip 36 preferably formed of sheet metal or like material is mounted in the rear of the notch 35 and has an opening 37 formed therein by punching 90 out a lip 38 from the body of the strip. The lip extends through the notch 35 and is bent back as shown at 39 against the rear surface of the plate 31.

The strip 36 is secured to the rear surface 95 of the plate 31 by a connection 40 of fusible metal, such as soft solder. In case of fire, the fusible connection 40 melts or is softened

to such an extent that the tension of the resilient supports 16 and 17 will cause the supports to spread apart and detach the strip 36 from the plate 31. As the resilient supports are released, the grenade will drop and break, thus extinguishing the fire. Furthermore, as the supports are released, the tension will cause the supports to swing about the pivot portions 25 thereof as shown in dotted lines in Fig. 3 and elbows 18 of the supports will exert a thrust against the grenade, forcing the grenade away from the wall as it drops. The impact of the elbows 18 against the frangible grenade will also tend to break the grenade and release the liquid.

From the foregoing description it will be seen that a simple and practical grenade support has been designed and that this support will in case of fire, quickly release the grenade. Furthermore, it should be noted that the fusible element or connector is located in a position spaced from the wall or other supporting structure on which the device is mounted and, therefore, will become heated and function more quickly than it would if the fusible element were located against the supporting bracket or plate 10 and in close proximity to the wall.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

- 40 1. A grenade support comprising a bracket, a pair of resilient grenade engaging and supporting elements carried by said bracket, and means, including a fusible element, engaging and holding said elements under tension whereby to support a grenade.
- 45 2. A grenade support comprising a bracket, a pair of resilient grenade engaging and supporting elements carried by said bracket and extending outwardly therefrom, and means, including a fusible element, engaging the outer ends of and holding said elements under tension whereby to support a grenade.
- 50 3. A grenade support comprising a bracket, a pair of resilient grenade engaging and supporting elements pivotally carried by said bracket, and means, including a fusible element, engaging and holding said elements under tension whereby to support a grenade.
- 55 4. A grenade support comprising a bracket, a pair of resilient grenade engaging and supporting elements pivoted in spaced relation to said bracket, said elements having means for limiting their pivotal movement toward each other, and means, including a fusible element, engaging and holding said elements

under tension whereby to support a grenade.

5. A grenade support comprising a bracket, a pair of resilient grenade engaging and supporting elements carried by said bracket, said elements having portions abutting against the bracket and having portions extending laterally therefrom, and means, including a fusible element, engaging the outer ends of said laterally extending portions of the resilient elements for holding the elements under tension whereby to support a grenade.

6. A grenade support comprising a bracket, a pair of resilient grenade engaging and supporting elements carried by said bracket, and heat controlled means spaced from said bracket and engaging said elements for holding the elements under tension.

7. A grenade support comprising a bracket, a pair of resilient grenade engaging and supporting elements carried by the bracket and adapted to spring apart, and heat controlled means engaging said elements for holding the elements under tension and in position to support a grenade.

8. A grenade support comprising a pair of resilient elements adapted to embrace and support the grenade, and fusible means for holding said elements under tension, said elements having portions adapted to move the grenade laterally when the elements are released.

9. A grenade support comprising a pair of resilient elements adapted to embrace and support the grenade, and fusible means for holding said elements under tension, said elements having portions adapted to exert a lateral pressure on the grenade when the elements are released.

10. A grenade support comprising a bracket, a pair of grenade engaging and supporting elements pivotally carried by said bracket, and means including a fusible element engaging said supporting elements and retaining said elements against relative pivotal movement, said elements being mounted on said bracket to partake of pivotal movement away from each other upon removal or failure of the fusible means.

11. A grenade support comprising a bracket, a pair of grenade engaging and supporting elements pivotally carried by said bracket, and means including a fusible element engaging said supporting elements and retaining said elements against relative pivotal movement, said elements being curved to embrace the grenade and mounted on said bracket to partake of pivotal movement away from each other upon removal or failure of the fusible means.

12. A grenade support comprising a pair of resilient elements adapted to embrace and support a grenade, and fusible means for holding said elements under tension and in position to support the grenade.

13. A grenade support comprising a pair

of resilient elements adapted to embrace and support a grenade, and fusible means engaging the ends of said elements for holding said elements under tension and in position to support the grenade.

14. A grenade support comprising a supporting member, means pivotally associated with said supporting member for supporting a grenade in one position of said means and for releasing said grenade upon pivotal movement to another position the arrangement being such that when the grenade and support are in assembled relation, the supporting means tends to assume said second position, and fusible means for holding the supporting means against pivotal movement in said first position.

15. A grenade support comprising a supporting member, and means including a fusible element carried by said supporting member for releasably supporting said grenade and for positively moving said grenade from the support on failure of said fusible member.

25 16. A grenade support comprising a supporting member, and pivoted means including a fusible element, carried by said supporting member for releasably supporting said grenade, constructed to partake of a pivotal lateral movement and positively move said grenade from the support on failure of said fusible member.

35 17. A grenade support comprising a bracket, means carried by the bracket for supporting a grenade, a fusible element controlling said supporting means, said supporting means being constructed to force the grenade away from the bracket when released by the fusible element.

40 18. A support for a fire extinguisher container comprising a bracket, a pair of separable members carried by the bracket and adapted to embrace and support a container, and fusible means for holding said members against separation and in position to support the container, said container being supported in position to cause separation of said members by its weight upon release thereof by said fusible means.

50 19. A support for a fire extinguisher container comprising a bracket, a pair of separable members carried by the bracket and adapted to embrace therebetween and support a container, and fusible means for holding said members against separation and in position to support the container, said container being supported in position to cause separation of said members by its weight upon release thereof by said fusible means.

60 20. In a support for fire extinguisher grenades, a pair of supporting members adapted to embrace therebetween a grenade and to support the grenade, and fusible means for retaining said members against separation, said container being supported in position

to cause separation of said members by its weight upon release thereof by said fusible means.

21. A support for fire extinguisher containers comprising a bracket, a pair of container embracing members carried by said bracket adapted together to support a grenade, one of said members being movable away from the other member, and fusible means retaining said members against separation, said container being supported in position to cause separation of said members by its weight upon release thereof by said fusible means.

70 22. A support for fire extinguisher containers comprising a bracket, a plurality of elements associated with said bracket for embracing and supporting the container, said elements being connected by heat controlled means, said container being supported 85 in position to cause a separation of said elements by its weight, upon release of the elements by the heat controlled means.

80 23. A support for fire extinguisher containers comprising a bracket, curved arms 90 carried by said bracket adapted to receive between them and to partially embrace the container, and means, including heat controlled means, secured to the outer ends of said arms for connecting said arms and embracing the remaining portion of the container, said container being supported in position to cause a separation of said arms by its weight upon release of the arms by the heat controlled means.

95 100 24. A support for fire extinguisher containers comprising a bracket, curved arms carried by said bracket adapted to receive between them and to partially embrace the container, and means, including heat controlled means, secured to the outer ends of said arms embracing the remaining portion of the container, said container being supported in position to cause a separation of said arms by its weight upon release thereof 110 by the heat controlled means.

105 25. A grenade support comprising a supporting member, means permanently associated with said supporting member for supporting a grenade, and fusible means for holding the supporting means in grenade engaging and supporting position, said latter means being incapable of supporting said grenade when free of said fusible member.

115 120 26. A grenade support comprising a supporting member, means pivotally associated with said supporting member for supportingly engaging a grenade, and fusible means for holding the supporting means against pivotal movement in grenade supporting position, said latter means when free of said fusible member, being movable to a non-supporting position upon subjection to the weight of the grenade.

125 27. A grenade support comprising a sup-

porting member, and means including a fusible element mounted thereon for supporting a grenade, said means being constructed to release the grenade from said support upon removal or failure of the fusible element.

28. A grenade support comprising a supporting member, and means including a fusible element carried by said supporting mem-

ber for releasably supporting said grenade, said support being constructed to positively move said means relative to said supporting member and to force said grenade from the support on failure of said fusible member.

In witness whereof, I have hereunto set my hand this 10th day of February, 1927.

WILHELM B. BRONANDER.
